ART OF CRACKING HYDROCARBON OILS

Filed Jan. 5, 1928

UNITED STATES PATENT OFFICE

EUGENE C. HERTHEL AND THOMAS DE COLON TIFFT, OF CHICAGO, ILLINOIS, ASSIGNEES TO SINCLAIR REFINING COMPANY, OF NEW YORK, N. Y., A CORPORATION OF MAINE

ART OF CRACKING HYDROCARBON OILS

Application filed January 5, 1928. Serial No. 244,683.

This invention relates to improvements in the cracking of higher boiling hydrocarbon oils, such as gas oil, to produce therefrom lower boiling hydrocarbon oils, such as gasoline. This application is in part a continuation of an application filed June 22, 1926, Serial No. 117,697 which has eventuated into Patent 1,677,773.

In addition to desired lower boiling oils, the products of cracking operations as usually carried out include gases incondensable except under high pressures and at low temperatures. These incondensable gases tend to carry with them uncondensed but condensable lower boiling constituents suitable as components of the desired lower boiling oil product. The recovery of such uncondensed but condensable constituents is of course desirable to improve the yield secured from the cracking operation, and a number of schemes have been used for this purpose.

For example, such gas mixtures have been subjected to scrubbing operations with special absorbent media from which absorbed condensable constituents are subsequently separated and recovered by distillation from the absorbent. Likewise, such gas mixtures have been subjected to scrubbing treatment with raw oil to be supplied to the cracking operation so that absorbable constituents are returned to the cracking operation in the raw oil again to escape with the gases and vapors from the cracking operation. Where such condensable constituents are reintroduced directly into the cracking operation proper, overcracking of such constituents frequently results. This overcracking can be avoided, for example, by introducing the raw oil, containing such absorbed condensable constituents into a refluxing operation to which the vapors and gases from the cracking operation are subjected so that absorbed condensable constituents are separated before the raw oil reaches the cracking operation proper, but this involves loss of heat which otherwise might be available in the cracking operation proper.

In continuous cracking operations, residual oil is usually withdrawn undistilled from the cracking operation proper. Such resid-

ual oils are with advantage expanded at a lower pressure for separation of oil constituents as vapors therefrom and these vapors in turn subjected to a refluxing operation for condensation of heavier components suitable to be returned to the cracking operation proper. Part of the heat of such residual oils, as discharged from the cracking operation, has been returned to the cracking operation proper by various expedients, but complete recovery of this heat is at least unusual in practical operation.

According to the present invention, uncondensed vapors and gases including condensable constituents, for example, gasoline components, are subjected to scrubbing treatment with raw oil to be supplied to the cracking operation and, before the raw oil with constituents absorbed in the scrubbing operation reaches the cracking operation proper, the heat of residual oil discharged from the cracking operation is utilized to distill such absorbed condensable constituents from the raw oil. Any possibility of overcracking such low boiling condensable constituents is thus avoided at the same time that an important heat economy is effected. This invention, moreover, provides a particularly advantageous way of effecting the heat transfer from residual oil to raw oil containing absorbed constituents.

According to the present invention, the residual oil discharged from cracking operation is expanded at a lower pressure for the separation of oil constituents as vapors therefrom, leaving a pitchy or coky residue, and the resulting vapors are subjected to a refluxing operation into which raw oil containing absorbed condensable constituents from the scrubbing treatment is directly introduced, lower boiling components of these vapors being taken off and condensed together with the condensable constituents vaporized from the raw oil while the absorption of heat in such vaporization assists in condensing the higher boiling components of the vapors being subjected to the refluxing operation, the unvaporized portion of the raw oil at the same time being preheated and thereby assisting in condensing the higher boiling components.

of the vapors and forming with the reflux condensate a hot oil mixture suitable to be supplied to the cracking operation proper. Objectionable constituents of the residual oil 5 discharged from the cracking operation are not included in this oil mixture as they are separated in the initial expansion of the residual oil.

The invention will be further described in 10 connection with the accompanying drawings which illustrate, in a diagrammatic and conventional manner, an apparatus adapted for carrying out the process of the invention.

The pressure still illustrated is of the general 15 type described in Letters Patent No. 1,285,200 issued November 19, 1918, to the Sinclair Refining Company on an application of Edward W. Isom. This particular type of pressure still is used simply for the 20 purposes of illustration.

This pressure still comprises a bulk supply 25 drum 1, a battery of vertical heating tubes 2, arranged in a heating furnace, and circulating connections 3, 4, and 5 including a circulating pump which is arranged to force oil from the bulk supply drum upwardly through the heating tubes and back to the bulk supply drum. Vapors from the bulk supply drum escape through connection 7 to pass 30 upwardly through reflux tower 8, uncondensed vapors escaping from the upper end of the reflux tower through connection 9 to condenser 12. This condenser discharges into receiver 13 from which the condensate is dis- 35 charged through connection 14, uncondensed vapors and gases escaping through connection 15. Raw oil may be introduced into the upper end of reflux tower 8 through connection 16. Some other refluxing medium, for 40 example, a light oil vaporizing substantially completely under the pressure and at the temperature prevailing in the reflux tower, may be introduced through connection 17. The refluxing operation in reflux tower 8 may be 45 effected or controlled by either or both of these means. Reflux, and any admixed unvaporized oil introduced into the reflux tower, is returned from reflux tower 8 to the circulating connection 3 through connection 18. Residual oil is discharged from the bulk supply 50 drum through connection 19 arranged to discharge into expander 20. Connection 21 is also provided for the introduction of oil into the pressure still. Cool oil for cooling and lubricating the bearings of the circulating pump is supplied through connection 22. Connection 23 is provided for initially charging the still at the beginning of a run and 55 for pumping out the still at the end of a run.

Uncondensed vapors and gases escaping through connection 15 are discharged into the lower end of scrubbing tower 24 through connections 25 and 26. Other hydrocarbon 60 gas mixtures including, for example, gaso-

line components may be supplied to the lower end of this scrubbing tower through connections 27 and 28. The stripped gas mixture escapes from the upper end of the scrubbing tower through connection 28 and 29. By-pass 30 is provided to cut out the scrubbing tower, partially or wholly, if this becomes necessary or desirable. Raw oil to be supplied to the cracking operation is introduced into the upper end of scrubbing tower 24 through connections 31 and 32 by means of pump 33. After passing through the scrubbing tower the raw oil, containing constituents absorbed in the scrubbing tower, flows through connection 34 to tank 35, this tank being provided to give flexibility to the operation. Additional raw oil may also be supplied to tank 35 through connection 36.

A pressure reducing valve 37 is provided in connection 19, advantageously at a point adjacent the pressure still, to control and release the pressure between the still and the expander 20. To promote the consequent vaporization in the expander, steam, or other hot gaseous medium may be introduced into the expander. Several baffles are arranged in the upper end of expander 20 to inhibit entrainment. Vapors escape through this expander through connection 38 into the lower end of tower 39 and unvaporized material is discharged through connection 40. The vapors from the expander pass upwardly through tower 39 and are subjected to reflux condensation therein, low boiling vapors escaping from the upper end of this tower through connection 41 to condenser 42. This condenser discharges into receiver 43 provided with a condensate outlet 44 and an outlet 45 for any uncondensed vapors and gases.

Raw oil containing condensable constituents absorbed in the scrubbing treatment is introduced into the upper end of tower 39 from tank 35 through connections 46 and 47 by means of pump 48. Some supplemental refluxing medium, for example, a light oil vaporizing substantially completely at the temperature and under the pressure prevailing in the tower, may also be introduced through connection 49. The absorbed condensable constituents are vaporized from the raw oil by the heat of the vapors escaping from expander 20, this vaporization of absorbed condensable constituents assisting in cooling and condensing the vapors from the expander 20, the latter vapors at the same time being further cooled and condensed by heat absorbed in preheating the unvaporized raw oil. Any low boiling components of these vapors and the absorbed condensable constituents vaporized from the raw oil escape through condenser 42 in which they are condensed, the condensate being collected in receiver 43. Any uncondensed vapors and gases remaining may also be subjected to the scrubbing

treatment, passing to the lower end of scrubbing tower 24 through connections 45, 25 and 26. The oil mixture collecting in the lower end of tower 39 is introduced into the pressure still by means of pump 50, either through connections 51 and 16 or through connection 21, or partly through each of these connections. It is advantageous to introduce as much as possible of this oil mixture through connection 16, but if the oil mixture is too hot more than a certain amount cannot be introduced into the upper end of reflux tower 8 while maintaining an appropriate temperature at the top of this tower, unless the vapors in the reflux tower are subjected to supplemental cooling. Such supplemental cooling may be supplied by introducing additional raw oil through connections 31, 52 and 16 or by introducing a supplemental refluxing medium through connection 17. Any part of the hot oil mixture not introduced through connection 16 may be introduced into the pressure still through connection 21.

Usually, a single scrubbing tower 24, expander 20, expander reflux tower 39, and associated condenser and receiver 42 and 43 may with advantage be combined with a number of cracking units. Connections 53, 54, 55, 56 and 57 are provided for connecting the recovery system, including the expander and expander tower, to a battery of pressure stills, each with an associated reflux tower. It will be understood that the hot parts of the apparatus as well as hot connections are advantageously lagged or heat insulated to prevent heat loss.

In operation, the pressure still is charged with sufficient oil and brought to cracking condition of temperature and pressure. In a still of the type illustrated, an initial charge of about 8,000 gallons of cool oil, say at a temperature of about 80° F., is commonly used. The pressure maintained during the operation is determined to a large measure by the stocks to be treated and the products to be obtained. With gas oil character charging stocks pressures up to 125 pounds per square inch or more may be used and with charging stocks containing large amounts of kerosene character components much higher pressures, say up to 300 pounds per square inch or more, may be used in the production of gasoline. The pressure in the still system may be maintained and regulated by means of valve 58 in the vapor line between the reflux tower and the condenser, or by valves arranged beyond the condenser or receiver. During the initial period of operation, residual oil is not discharged from the pressure still, or is discharged in but small amount, but before the pitch concentration in the charge of oil in the pressure still reaches an objectionable value the discharge of residual oil is begun and the rate of discharge is regulated, with respect to the rate at which raw

oil is supplied, to maintain the concentration of pitch in the pressure still charge below an objectionable value. The residual oil is discharged into expander 20 where a pressure substantially lower than that prevailing within the pressure still is maintained, the pressure between the still and the expander being reduced by means of valve 37. Due to this reduction in pressure, the discharged residual oil is subjected to further vaporization, vapors entering reflux tower 39 and pitchy or coky components separating in a residue remaining unvaporized. The degree of vaporization in the expander can be controlled by regulating the pressure therein. As much as 80% or more of the residual oil may be so vaporized, but if a liquid residue is to be obtained it is usually not desirable to go much beyond this point and it may be necessary to reduce the amount of vaporization, although a liquid residue can sometimes be obtained with vaporization of as much as 90% or more of the residual oil. With still pressures in the neighborhood of 100 pounds per square inch or higher, the pressure in the expander may be maintained at a value between atmospheric pressure and say 50 pounds per square inch or higher, depending upon the amount of vaporization desired. In the production of gasoline from a gas oil character stock, for example, the temperature at the top of reflux tower 8 may be maintained at about 550° F. and the temperature at the top of expander reflux tower 39 at about 350° F. The temperature at the top of reflux tower 8 is maintained by regulated introduction of raw oil or the oil mixture from tower 39 through connection 16 or of a mixture of cool raw oil and the hot oil mixture from tower 39 through this connection, or by the introduction of some other refluxing medium, such as a part of the distillate product, through connection 17, or by these means conjointly. The temperature at the top of expander reflux tower 39 is maintained by the regulated introduction of raw oil through connection 47, supplemented as may be necessary by the regulated introduction of some other refluxing medium, such as a part of the distillate product, through connection 49. The temperature of the oil mixture collecting in the bottom of expander reflux tower 39 may approximate 450°-480° F., and it is usually desirable to limit the temperature of the oil or oil mixture introduced into reflux tower 8 to a value not exceeding 275° to 280° F. to maintain a head temperature approximating 550° F., unless some supplementary refluxing medium is used in the latter tower. While the invention has been described particularly as applied to the recovery of uncondensed but condensable constituents from gas-vapor mixtures from cracking operations, the invention is also useful in more general applications for the recovery of such

uncondensed but condensable constituents from hydrocarbon gas mixtures from other sources, for example, from other refinery gases, tank gases and the like.

5 We claim:

1. In cracking hydrocarbon oils, the improvement which comprises heating a charge of oil to a cracking temperature under pressure taking off vapors and gases therefrom and subjecting them to a condensing operation, subjecting uncondensed vapors and gases from the condensing operation to scrubbing treatment with raw oil to be supplied to the cracking operation, discharging residual oil from the first mentioned charge of oil and reducing the pressure thereon, thereby causing vaporization of part of said residual oil, subjecting the resulting vapors to a refluxing operation, introducing raw oil with absorbed constituents from the scrubbing treatment into direct contact with the vapors in this refluxing operation, and taking off and condensing the vapors from this refluxing operation.
2. In cracking hydrocarbon oils, the improvement which comprises heating a charge of oil to a cracking temperature under pressure, discharging residual oil from this charge of oil and reducing pressure thereon, thereby causing vaporization of parts of said residual oil, subjecting the resulting vapors to a refluxing operation, subjecting a hydrocarbon gas mixture containing uncondensed but condensable hydrocarbons to scrubbing treatment with raw oil to be supplied to the cracking operation, introducing raw oil with absorbed constituents from this scrubbing treatment into direct contact with the vapors in the said refluxing operation, and taking off and condensing the vapors from the said refluxing operation.
3. In cracking hydrocarbon oils, the improvement which comprises subjecting a hydrocarbon gas mixture containing uncondensed but condensable constituents to scrubbing treatment with raw oil to be supplied to the cracking operation, discharging residual oil from the cracking operation, vaporizing absorbed constituents from the raw oil from the scrubbing operation while under a lower pressure than that maintained on the oil in the cracking operation by heat given up by this discharged residual oil, condensing the resulting vapors, and supplying the raw oil after vaporization of absorbed constituents therefrom to the cracking operation.

In witness whereof, we have subscribed our names.
